UNITED STATES PATENT OFFICE.

JOHN G. HANKS, DECEASED, BY ELIZA P. BROWN, ADMINISTRATRIX, OF OAKLAND, CALIFORNIA.

RANGE-FINDER.

1,286,609.

Specification of Letters Patent.

Patented Dec. 3, 1918.

Application filed March 12, 1917. Serial No. 154,397.

To all whom it may concern:

Be it known that I, ELIZA P. BROWN, a citizen of the United States, residing at Oakland, county of Alameda, and State of California, administratrix of the estate of JOHN G. HANKS, late a citizen of the United States, deceased, do hereby make application for certain new and useful Improvements in Range-Finders invented by the said JOHN G. HANKS, of which the following is a specification.

This invention relates to an improvement in so-called "range-finders", that is to say instruments for measuring and determining distances by parallax on land or at sea from a fixed point by the intersection of visual lines, also with other functions, such as determining in a horizontal plane the relative movement of distant objects, it being an improvement on an application filed in the U. S. Patent Office by John G. Hanks, deceased, December 17, 1907, Serial No. 406,915.

This present invention relates more particularly to improvements wherein the base of the truss carrying the range-finding mechanism operates in conjunction with rotating means supported on the base of a tripod; and this invention consists in improved means for rotating the mechanism in a horizontal plane. It consists further in means for disengaging the rotating mechanism from the range-finding mechanism, and means for securing the rotating mechanism against turning upon the base.

In the accompanying drawings:—

Figure 1 is a side elevation of the device with the lower portion of the legs of the tripod partly broken away;

Fig. 2 is a plan view of Fig. 1, disclosing the range-finder focused on a distant object;

Fig. 3 is a view similar to Fig. 2 after the object has moved and the range-finding mechanism has been partially rotated, the rear mechanism having remained stationary;

Fig. 4 is a plan view of the rotating mechanism on a large scale disclosing the rotating means secured to the base-plate of the range-finding mechanism;

Fig. 5 is a broken side elevation of Fig. 4;

Fig. 6 is a vertical sectional view on line 6—6 of Fig. 4.

The numeral 1 designates a base-plate mounted upon a tripod 2. An annular flange ring 4 is rotatably mounted upon the base plate 1, and is retained in position by means of suitable clamps 5.

A second annular flange 3 is rigidly mounted on the base-plate 1 by means of screws or like devices. I may also provide a hardened steel race-way 3'. The parts 3, 3' are rigidly united and mounted on plate 1 to form a support for the top plate 6 which is rotatably mounted upon the annular flange 3, and is provided with a recess 6' in which the upper portion of the ring 3 is fitted. This top plate 6 is further provided with a worm gear 7, which is adapted to be engaged by a worm 8 secured to a shaft 9 rotatably mounted in suitable bearings 10 and 11. The outer end of the shaft 9 is provided with a suitable disk 12 to which is secured a suitable handle 14 by means of which the said disk 12 and shaft 9 may be rotated.

An extension bearing 15 is secured to the annular flange 4 for the purpose of further supporting the outer end of the shaft 9.

The bearing 11, at the inner end of the shaft 9 is provided with an extension 16 which is slidably mounted within a sleeve 17 secured to a suitable bracket 18, which is in turn secured to the annular flange 4.

The extension 16 of the bearing 11 is notched as at 20, said notch being engaged by means of a suitable thumb-screw 21. By loosening screw 21 and screwing adjusting nut the worm will be drawn out of mesh. When the end of the thumb-screw 21 engages 90 the notch 20, the bearing 11 will retain the worm 8 in engagement with the worm-gear 7. A thumb-nut 25 is provided on the inner end of the shaft 9 so that the said shaft 9 may be rotated from that end, if desired. 95

The operation is as follows:—

The object is sighted by means of the right-hand telescope A, and the telescope B is turned by means of the handle C and the worm D, which engages the sector E secured 100 to the pivot F of the telescope B.

In order to retain the moving image with-

- in the approximate center of the telescopes A and B, which have been focused thereon, the truss-bar G, which forms a supporting frame for the said telescopes A and B and 5 which is rigidly secured to the top plate 6, the handle 14 of the disk 12, is rotated, which causes the shaft 9 to rotate the worm 8 and thereby rotate the worm-gear 7 secured to the top plate 6.
- 10 The annular flange 4 may, at any time, be retained against movement by means of the thumb screw 30, which is connected thereto and adapted to engage the base plate 1. By loosening the said screw 30, the entire structure above the base 1 may be rotated, except for the stationary portions 3, 3' and 3".

If it is desired to turn the rotating mechanism, by loosening the screw 30 and then 20 disengaging the thumb-nut 21 from the notch 20 of the extension 16, the said extension 16 may be moved outward in the sleeve 17, within which it is slidably mounted, and thereby disengage the worm 8 from 25 the worm gear 7, when the rotating mechanism can be easily rotated on the base-plate 1 without rotating the range-finding mechanism.

This machine can be operated by one person standing in one place, by loosening screw 21, thus disengaging worm and worm gear, and swinging truss bar into any position desired. By then loosening adjusting screw and putting worm in mesh and tightening screw 21, the movement of the truss bar can be obtained by turning disk 12, provided screw 30 is tightened.

I claim:

1. In a distance-measuring instrument, the 40 combination of a base-plate, an annular flange rotatably supported thereon and capable of being secured thereto, a second annular flange mounted on said base-plate, a top-plate rotatably mounted upon said second annular flange, a truss-bar carried by the top-plate, and telescopes carried at opposite ends of the truss-bar.
2. In a distance-measuring instrument, the 50 combination of a base-plate, an annular flange rotatably supported thereon and capable of being secured thereto, a second annular flange mounted on said base-plate, a top-plate rotatably mounted upon said second annular flange, a truss-bar carried by the top-plate, the top-plate having a worm-gear, and a worm carried by the annular flange for engaging and turning said worm-gear.
3. In a distance-measuring instrument, 60 the combination of a base-plate, an annular flange rotatably supported thereon and capable of being secured thereto, a second annular flange mounted on said base-plate, a top-plate rotatably mounted upon said second annular flange, a truss-bar carried by

the top-plate, the top-plate having a worm-gear, a worm carried by the annular flange for engaging and turning said worm-gear, and means on either end of said worm whereby to turn the latter.

4. In a distance-measuring instrument, the combination of a base-plate, an annular flange rotatably supported thereon and capable of being secured thereto, a second annular flange mounted on said base-plate, a top-plate rotatably mounted upon said second annular flange, a truss-bar carried by the top-plate, the top-plate having a worm-gear, a worm carried by the annular flange for engaging and turning said worm-gear, and an adjustable bearing through which the worm turns for holding the latter in or out of engagement with the worm-gear.

5. In a distance-measuring instrument the combination of a base-plate, an annular flange rotatably supported thereon and capable of being secured thereto, a second annular flange mounted on said base-plate, a top-plate rotatably mounted upon said second annular flange, a truss-bar carried by the top-plate, the top-plate having a worm gear, a worm carried by the annular flange for engaging and turning said worm-gear, an adjustable bearing through which the worm turns for holding the latter in or out of engagement with the worm-gear consisting of a slidable extension having a bearing at one end, through which the worm turns, provided with a notch, a sleeve in which the extension is supported, and a thumb-nut which turns in the sleeve in position to engage the notch to hold the extension in place in the sleeve with the worm and worm-gear intermeshed.

6. In a distance-measuring instrument 105 the combination of a base-plate, an annular flange rotatably supported thereon and capable of being secured thereto, a second annular flange mounted on said base-plate, a top-plate rotatably mounted upon said second annular flange, a truss-bar carried by the top-plate, telescopes carried by the truss-bar, the top-plate having a worm gear, a worm carried by the annular flange for engaging and turning said worm-gear, and means carried by the annular flange for holding the worm and worm-gear in or out of mesh with each other.

7. In a distance-measuring instrument, the combination of a base-plate, an annular flange rotatably supported thereon and capable of being secured thereto, a second annular flange mounted on said base-plate, a top-plate rotatably mounted upon said second annular flange, a truss-bar carried by the top-plate, telescopes carried by the truss-bar, the top-plate having a worm-gear, a worm carried by the annular flange for engaging and turning said worm-gear, means carried by the annular flange for 125

holding the worm and worm-gear in or out of mesh with each other, and means for securing the annular flange to the base-plate.

8. In a distance-measuring instrument, the combination of a base-plate, a supporting ring, a race-way, an annular flange ring, so connected together as to form a rigid support, a truss-bar rotatably supported thereon, and means supported on the base-plate for 10 turning the truss-bar.

In testimony whereof, I affix my signature, as administratrix of the estate of JOHN G. HANKS, deceased, in the presence of two witnesses.

ELIZA P. BROWN,
*Administratrix of the estate of John G.
Hanks, deceased.*

Witnesses:

E. LORENSEN,
J. M. C. MURPHEY.
